(57) **CLAIM**

The ornamental design for a dog collar training aid, as shown and described.

DESCRIPTION

FIG. 1 is a front perspective view of a dog collar training aid showing my new design;

FIG. 2 is a rear perspective view thereof;

FIG. 3 is a front elevational view thereof;

FIG. 4 is a rear elevational view thereof;

FIG. 5 is a top plan view thereof, the bottom plan view being basically the same;

FIG. 6 is a left side elevational view thereof, the right side elevational view being the same;

FIG. 7 is a reduced scale front perspective view thereof, the broken lines of a collar are for illustrative purposes only and forms no part of the claimed design;

FIG. 8 is a front perspective view of a second embodiment of a dog collar training aid showing my new design;

FIG. 9 is a rear perspective view thereof;

FIG. 10 is a front elevational view thereof;

FIG. 11 is a rear elevational view thereof;

FIG. 12 is a top plan view thereof, the bottom plan view being the same; and,

FIG. 13 is a left side elevational view thereof, the right side elevational view being the same.
